UNITED STATES PATENT OFFICE.

WILLIAM J. KEEP, OF DETROIT, MICHIGAN.

DESIGN FOR A WATER-TANK FOR STOVES.

SPECIFICATION forming part of Design No. 22,741, dated August 22, 1893.

Application filed May 6, 1893. Serial No. 473,303. Term of patent 14 years.

To all whom it may concern:

Be it known that I, WILLIAM J. KEEP, a citizen of the United States, residing at Detroit, county of Wayne, State of Michigan, have invented a certain new and useful Design for a Stove Water-Tank; and I declare the following to be a full, clear, and exact description of the invention, such as will enable others skilled in the art to which it pertains to make and use the same, reference being had to the accompanying drawings, which form a part of this specification.

This invention relates to stoves, and has for its object a design appropriate to be used at the end of the water tank commonly attached to kitchen stoves.

In the drawings Figure 1 shows an elevation of the end of the water tank embodying my design. Fig. 2 shows an outline sketch of a stove with the water tank attached to the rear thereof, to indicate the position in which the water tank, made according to my design is to be attached to the stove.

A, indicates the cast iron coating at the end

of the water tank, at the lower side of which is a triangular bracket having an irregular scroll outline on its lower rear side, the volutes of the several scrolls being continued over the surface of the end of the tank, as high or somewhat higher than the top of the oblique under and rear sides, *a*. Above the lower ornamental portion described is a perfectly smooth unornamented portion extending to the front of the tank and to the top of tank. The ornamental scroll work thus comprises the bottom portion while the remainder of the plate is nearly all smooth. The entire plate is convex outward as shown.

What I claim is—

A design for a water tank of a cooking stove as shown and described.

In testimony whereof I sign this specification in the presence of two witnesses.

WILLIAM J. KEEP.

Witnesses:

ISAAC S. FILER,
S. E. WIDDIFIELD.
